UNITED STATES PATENT OFFICE

2,484,571

COMBINED DEAD BOLT AND LATCH BOLT
LOCK

Ignacy Jozefowicz, Kenosha, Wis.

Application April 19, 1946, Serial No. 663,456

2 Claims. (Cl. 70—107)

1

My invention relates to locks and more particularly to locks adapted to fit a conventional type of door.

The object of my invention is to provide a combination device that will operate both a conventional lock and latch.

Another object of my invention is to provide a lock that requires the manipulation of both the key, lock and latch in a synchronized manner for its complete operation.

Still another object of my invention is to incorporate a specially designed key and latch barrel in its construction.

A still further object of my invention is to construct the latch barrel in a manner to prevent its removal even though the latch actuating means is removed from the outside of the door.

Other and further objects of my invention will become more apparent as the description proceeds when taken in conjunction with the drawings, in which:

Figure 1 is a plan view of the entire device with the top plate removed and the latch bolt and lock in a locked position.

Figure 2 is a view similar to Figure 1, with the latch barrel turned, thereby retrieving the latch toward an open position.

Figure 3 is a similar view, as shown in Figures 1 and 2, with the key turned to retrieve the lock member to a pre-determined position.

Figure 4 is a similar view showing the actuation and disengaging of the vertical sliding member to permit further movement of the lock.

Figure 5 is a similar view showing both the latch and lock in an unlocked position.

Figure 6 is a front view of the entire lock assembly.

Figure 7 is a perspective view of the entire assembly with the latch actuating member and the key in position.

Figure 8 is a cross-sectional view of the assembly, taken at the line 8—8 in Figure 1.

Figure 9 is a cross-sectional view of the assembly, taken at the line 9—9 in Figure 5.

Figure 10 is a cross-sectional view of the lock as shown in line 10—10 in Figure 1.

Figure 11 is a cross section taken at the line 11—11 in Figure 1.

Figure 12 is a cross section of the assembly taken at the line 12—12 in Figure 1.

Figure 13 is a cross-section of the assembly shown in Figure 1, taken at the line 13—13.

Figure 14 is a side view of the key illustrating the operation and assembly of the pivot member.

2

Figure 15 is a top view of the shank of the key shown in Figure 14.

Figure 16 is a side view of the latch barrel with one of the latch actuating members in position.

Figure 17 is a cross section of Figure 16 taken at the line 17—17 therein.

Similar characters of reference indicate corresponding parts throughout the several views, and referring now to the same, the character 20 indicates a lock housing or enclosure having a front plate 21, an upper plate 22, a lower plate 23, a rear plate 24 and a back plate 25. A removable cover plate 26 acts as a closing means when attached by means of the screw 27 threadedly engaging the inwardly extending threaded member 28 terminating from the back plate 25. The entire assembly is retained in position while inserted into a door, by means of the two screws 29 inserted into the countersunk holes 30 in the front plate 21.

A cross member consisting of two halves 31 and 31' slidably engages guide members 32 extending inward from the upper and lower plates 22 and 23 respectively. A sliding member 33 slidably engages the cross member 31 and acts as a retaining means when engaging the recessed portion 34 in the lock bolt 35. This lock bolt 35 extends through the front plate 21 and is kept from disengagement by the projecting portion 36 integrally formed therewith. The bolt 35 is slidably supported by the cross member 31, 31'. There is a latch member 37 of rectangular or square cross section engaging and extending through the front plate 21. A latch bolt 38 threadedly engages this member 37 at 39. A resilient member 40 encircles the latch bolt 38 and is disposed between the cross member 31, 31' and the latch member 37, and has for its purpose to urge the bolt 38 outward. The inwardly projecting end of the bolt 38 is provided with a beveled head 41 having a contact member 42 which engages a member 43 extending inwardly from the upper plate 22. The engagement of the member 42 with the member 43 prevents the resilient member 40 from forcing the bolt 38 outward too far.

In Figures 16 and 17 is shown a latch barrel 44 threaded at both ends and provided with handles 45 shown having their depending ends disposed downwardly and being held in engagement with the barrel 44 by means of the screw 46. The barrel 44 may be provided with apertures through the entire unit and the screw 46 may extend through the aperture in the barrel.

There is a pivoted member 47 mounted within an elongated slot 48 and hingedly attached near

55

one end of the slot. The back plate 25 and the cover plate 26 of the housing 20 are provided with apertures 50 through which the barrel 44 is inserted, and the handles 45 are attached at both ends of the barrel in close contact with the outside face of the back plate 25 and the cover plate 26. When in this position, the pivoted member 47, being supported by the pin 49 at one end, will permit its depending end to drop downwardly, bringing it in direct alignment with the head 41, and as the barrel 44 is revolved in the proper direction the bottom edge of the pivoted member 47 will contact the angular face of the beveled head 41.

The lock bolt 35 is slidably supported by the cross member 31, 31' and is provided with a V shaped recess 51 at its upper face and a series of beveled steps 52 and 53 at its extreme end.

A key 54, shown in Figures 14 and 15, is provided with a similar pivoted member 55 mounted within a slot 56 by means of a pin 57. The back plate 25 and the cover plate 26 are provided with apertures at 58 and the key 54 is inserted into these apertures thereby permitting the pivoted member 55 to drop downwardly at the depending end in direct alignment with the lock bolt 35 for engagement with the V-shaped recess 51.

The retaining lever 59 is pivotally mounted on the screw 60 engaging the rear plate 24, and is deflected about the pivot 60 by contact of the cam face 62 on head 41 with the radially formed end 61 of the lever 59. The pivoting of the lever 59 is accomplished by the latch bolt 38 being urged laterally by means of the element 47 on the latch barrel 44.

The movement of the pivoted lever 59 causes the end 61 to move in one direction while the other end 63 moves in the opposite direction against the tension of the spring 64 mounted on the pivot 60 thereby permitting engagement and disengagement of the end 63 with the steps 52 and 53 on the inner end of the lock bolt 35.

The sliding member 33 is urged downwardly toward the recess 34 in the lock bolt 35 by means of a resilient member 65 attached at 66 to the sliding member 33 and at 67 to the lower plate 23.

In operation, the lock functions as follows:

In neutral locked position the lock bolt 35 and latch member 37 extend outward from the plate 21 as shown in Figure 1. As the barrel 44 is turned, the pivot member 47 pushes against the angular surface of the beveled head 41, as shown in Figure 2, forcing the end 61 of the lever 59 and retrieving the latch member 37. As the end 61 of the lever 59 is pushed, it will move the end 63 of the lever 59 permitting the pivoted member 55 on the key 54 to push the lock bolt 35 for slidable engagement with the end 63 to the first step 53. The bolt 38 is again released, as shown by the dotted lines in Figure 4, and the pivoted member 47 on the barrel 44 is forced upward against the extending ledge 68 of the sliding member 33, thereby disengaging the member 33 from the recess 34 in the lock bolt 35, as shown in Figure 4, which permits the member 55 of the key 54 to push the end of the lock bolt 35 for slidable engagement with the end 63 of the pivoted lever 59 to the second step 52 as shown in Figure 5, thereby retrieving the bolt 35 all the way and when the barrel 44 is again brought in position, as shown in Figure 5, the latch member 37 is also retrieved and the lock is in an open position.

With the arrangement of the pivoted member 47 in the barrel 44 the barrel can be removed in only one direction and the member 47 would not permit the barrel to be pulled out from the opposite direction.

In the chosen embodiment of my invention, there are present many features not heretofore disclosed in the prior art. However, I am fully cognizant of the fact that many changes in the form and configuration of the various elements constituting the entire assembly may be made without affecting their operation or function, and I reserve the right to make such changes as I may deem convenient and necessary without departing from the spirit of my invention or the scope of the appended claims.

Having thus described my invention, what I claim and desire to secure by Letters Patent in the United States is:

1. A lock assembly of the character described comprising in combination, a rectangular housing, a spring actuated latch bolt, an actuating means for slidably moving said latch bolt against the tension of said spring, a slidably supported lock bolt, both of said bolts encased within said housing and caused to project outward at one end thereof, a rotatable barrel provided with a pivoted extending member, said barrel supported by the walls of said housing and employed as an actuating means for slidably moving said latch bolt, a key, said key provided with a pivoted extending member, said key supported by said housing and employed as an actuating means for slidably moving said lock bolt, a sliding member supported by and within said housing, said sliding member engaging a recess in said lock bolt, a resilient means for urging said sliding member into the recess in said lock bolt, the barrel employed as an operating means for said latch bolt being employed as a means for disengaging said sliding member from the recess in said lock bolt, and a pivoted lever supported by one of the walls of said enclosure, said pivoted member retaining said bolts in proper alignment to permit the synchronized action of said barrel and key for movement of said bolts.

2. A lock of the character described comprising in combination a housing, a latch bolt, a lock bolt, said bolts slidably mounted within said housing, separate actuating means for slidably moving said bolts, both of said bolts permitted to extend outward from one end of said housing, sliding means supported within said housing, said sliding means engaging a recess in said lock bolt, a resilient means for urging said sliding means into said recess, the actuating means of said latch bolt employed to disengage said sliding member from the recess in said lock bolt, and a pivoted member supported by one of the walls of said enclosure for controlling the movement of said bolts while being slidably actuated in parallel relation to one another.

IGNACY JOZEFOWICZ.
